(57) **CLAIM**

The ornamental design for the self-feed bit, as shown and described.

DESCRIPTION

FIG. 1 is a perspective view of a self-feed bit in accordance with our invention;

FIG. 2 is a front view of the self-feed bit of FIG. 1;

FIG. 3 is a rear view of the self-feed bit of FIG. 1;

FIG. 4 is a left side view of the self-feed bit of FIG. 1;

FIG. 5 is a right side view of the self-feed bit of FIG. 1;

FIG. 6 is a top view of the self-feed bit of FIG. 1; and,

FIG. 7 is a bottom view of the self-feed bit of FIG. 1.

The dash-dot-dash broken lines of FIGS. 1-7 illustrate an unclaimed boundary, while all other broken lines of FIGS. 1-7 are included for the purpose of illustrating portions of the self-feed bit that form no part of the claimed design.

1 Claim, 7 Drawing Sheets
